Primary Examiner — Sheryl Lane*Assistant Examiner* — Mark T. Philipp(74) *Attorney, Agent, or Firm* — WPAT, PC(57) **CLAIM**

The ornamental design for a digital inflator, as shown and described.

DESCRIPTION

FIG. 1 is a perspective view of a digital inflator showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an exemplary perspective view showing the digital inflator being used to pump; and,

FIG. 9 is an enlarge drawing of the area A annotated in FIG. 6.

The broken lines in FIG. 8 are for illustrating the cables connected to the digital inflator and forms no part of the claimed design. The broken lines in FIGS. 6 and 9 define the boundary of the enlarged view and form no part of the claimed design.
